UNITED STATES PATENT OFFICE.

THOMAS SILLS, OF WESTMOUNT, QUEBEC, CANADA.

GRAIN-CAR DOOR.

1,073,296.

Specification of Letters Patent. Patented Sept. 16, 1913.

Application filed April 2, 1912. Serial No. 687,949.

To all whom it may concern:

Be it known that I, THOMAS SILLS, a resident of 113 Lewis avenue, in the city of Westmount, in the Province of Quebec, in 5 the Dominion of Canada, a subject of the King of Great Britain, have invented certain new and useful Improvements in Grain-Car Doors; and I do hereby declare that the following is a full, clear, and exact description of the same.

The invention relates to improvements in a grain car door, as described in the present specification and illustrated in the accompanying drawings that form part of the 15 same.

The invention consists essentially in the novel arrangement and construction of parts, whereby a readily operated locking mechanism is employed for securely holding the door in its closed position, and other means utilized for lifting and transporting said door for storage within the car when out of commission.

The objects of the invention are to devise a door which is a permanent attachment to the car and cannot readily be removed therefrom, to prevent loss of grain, to facilitate the opening of the door for discharging purposes, and generally to provide a comparatively cheap and very durable form of grain car door.

In the drawings Figure 1 is a perspective view showing the door in its closed position. Fig. 2 is a longitudinal sectional view on the line A—B in Fig. 1. Fig. 3 is an enlarged sectional perspective view of the trolley and track. Fig. 4 is an enlarged cross sectional view of the door and car wall on the line C—D in Fig. 1, showing said door 40 broken away at the center thereof. Fig. 5 is a front elevation of a metal car door. Fig. 6 is an enlarged perspective detail of the rotary lever. Fig. 7 is an enlarged view showing elevations of the cover plate and locking plate respectively. Fig. 8 is an enlarged sectional view of a modified form of locking mechanism. Fig. 9 is an enlarged sectional view of the form shown with a single plank door. Fig. 10 is an enlarged 45 perspective detail of the distance piece between the cover plates at the top of the door. Fig. 11 is an enlarged perspective detail of the distance piece between the cover plates at the bottom of the door. Fig. 12 is an enlarged cross sectional view, showing the locking slot differently placed. Fig. 13 is

an enlarged cross sectional view through the line E—F in Fig. 1.

Like numerals of reference indicate corresponding parts in each figure.

Referring to the drawings, 1 is the wall of the car having the door opening 2 therethrough, said door opening being framed by the posts 3 and 4, the upper beam 5 and the sill 6.

7 and 8 are vertical slots at each side of the door opening, contiguous to, or in, the posts 3 and 4, said slots having the linings 9 and 10 of sheet metal.

11 is the door formed with the vertical 70 slot 12 in one of its side edges.

13 is a metal plate binding over the opposite vertical edge from the slot 12 and extending inwardly of the door on the outer and inner sides thereof, and having centrally 75 in relation to said side edge, the jutting piece 14, said jutting piece extending into the vertical slot 8 and said binding plate secured to the door by the rivets 15.

16 is a locking plate having the reduced 80 upper end 17 and the reduced lower end 18, the lever holes 19 and the distance piece holes 20, said locking plate 16 being introduced into the vertical slot 12, and in the open position of the door sliding to the extreme inner wall of said slot 12 and in the closed position of the door, extending into the vertical slot 7.

21 are distance pieces extending across the slot 12 and through the door from said slot 90 to the door surface.

22 and 23 are cover plates having the journal orifices 24 and 25, each journal orifice 24 registering with the journal orifice 25 through corresponding holes in the door extending across the slot 12.

It will now be seen that the door 11 has on one side edge a jutting piece extending from top to bottom thereof into the slot 8, thus firmly holding that side of the door 100 to the car, while the locking plate 16, in the closed position of the door extends beyond the other side edge into the slot 7, said locking plate 16 being supported in said slot 12 by the distance pieces 21, and said distance pieces 21 being firmly fastened in place between the said cover plates 22 and 23 by the bolts or rivets 26.

27 are rotary levers having the body portions 30 journaled in the orifices 24 and 25, 110 and the cam portion 31 projecting laterally from said body portions 30 in alinement

with the locking plate 16 and in the lever holes 19, said body portion having squared key holes 32, extending thereinto at each end.

33 is a distance block between the cover plates 22 and 23, and suitably formed to correspond with the reduced upper end 17, of the locking plate 16. 34 is a distance block at the lower end of said locking plate, 10 and between the cover plates 22 and 23.

The operation of the locking plate will now be readily understood. As the rotary levers 27 are turned by a suitable key wrench, the action brings the cam extension 15 to one or the other side of the lever holes 19, said cam extension thus engaging said locking plate and sliding it in the vertical slot 12, either inwardly or outwardly as the case may be. In sliding it inwardly, 20 the door is unlocked and the grain will pour out from weight alone, and in sliding it outwardly, the said locking plate will project into the slot 7 and hold the door firmly locked against the weight of the grain.

35 is a bracket secured to the door 11 centrally at the upper end thereof, said bracket having the eye 36 projecting beyond the upper edge of the door.

37 is a lever having the eye hole 38 at 30 the lower end thereof, and the eye hole 39 intermediate of the length thereof.

40 is a chain connecting the eye 36 with the eye 38, thus forming a connection between the door and the lever.

35 41 is a trolley track extending along the inner wall of the car above the door-way 2, and beyond said door-way toward the end wall of the car, said track having the downwardly extending flange 42 at the outer end 40 thereof.

43 are trolley wheels running on the track 41.

44 is a trolley hanger having the retaining flange 45 extending upwardly inside of 45 the flange 42, and the pin 46, on which the wheels 43 are journaled, said hanger at the lower end having the eye 47 joined to the eye 39 by the chain 48.

It will now be seen that by pulling downwardly on the lever 37, the upper end of 50 the chain 40 is elevated, consequently rais-

ing the door 11 so that the door can be cleared at its lower end and swung inside of the car, then said door is run on its trolley support along the inner wall of the car 55 to the place where it is desired to store it, when out of commission.

The advantages of this invention are many, but the chief features are the locking mechanism and the transport means for 60 storage, however, many of the details are also very important as in construction they save considerable expense.

The steel door shown in the drawings, is simply another means for manufacturing 65 this invention and, of course, in that particular form, some of the details as described are eliminated as the entire metal construction renders it necessary, but it is not desirable to lengthen out this specification by describing a great many different forms, as the salient features have already been mentioned generally.

What I claim as my invention is:—

In a grain car door, the combination with 75 the car body having a door opening in the side thereof and vertical recesses in the frame of said door opening, of a door having a permanent piece extending into one of said vertical recesses at one side and at the 80 other side a vertical slot registering with the other vertical recess in door frame, inner and outer face plates having a plurality of journal orifices communicating with said slot, a locking plate slidable laterally in its said slot and having a plurality of substantially rectangular openings therethrough registering with the aforesaid journal orifices, a plurality of cam levers having a journal end bearing in said 85 journal orifices, a squared key recess from their outer sides and a cam extension adapted to engage the vertical walls of said openings in the locking plate and adapted to operate said laterally sliding plate. 95

Signed at Montreal Canada this 5th day of February 1912.

THOMAS SILLS.
